CLAIM

The ornamental design for an infant feeding device, as shown and described.

DESCRIPTION

FIG. 1 is a perspective view of an infant feeding device according to one embodiment of our new design;

FIG. 2 is a front view of the infant feeding device of FIG. 1;

FIG. 3 is a rear view of the infant feeding device of FIG. 1;

FIG. 4 is a left side view of the infant feeding device of FIG. 1;

FIG. 5 is a right side view of the infant feeding device of FIG. 1;

FIG. 6 is a top view of the infant feeding device of FIG. 1;

FIG. 7 is a bottom view of the infant feeding device of FIG. 1;

FIG. 8 is a perspective view of an infant feeding device according to an alternative embodiment of our new design;

FIG. 9 is a front view of the infant feeding device of FIG. 8;

FIG. 10 is a rear view of the infant feeding device of FIG. 8;

FIG. 11 is a left side view of the infant feeding device of FIG. 8;

FIG. 12 is a right side view of the infant feeding device of FIG. 8;

FIG. 13 is a top view of the infant feeding device of FIG. 8; and,

FIG. 14 is a bottom view of the infant feeding device of FIG. 8.

The broken lines shown in the figures are for illustrative purposes, and form no part of the claimed design.
